UNITED STATES PATENT OFFICE.

JOHN M. KROYER, OF STOCKTON, CALIFORNIA.

TRACTOR-WHEEL.

1,109,294.

Specification of Letters Patent.

Patented Sept. 1, 1914.

Application filed April 15, 1912. Serial No. 761,168.

To all whom it may concern:

Be it known that I, JOHN M. KROYER, a citizen of the United States, residing at Stockton, in the county of San Joaquin, State of California, have invented certain new and useful Improvements in Tractor-Wheels; and I do declare the following to be a clear, full, and exact description of the same, such as will enable others skilled in the art to which it appertains to make and use the same, reference being had to the accompanying drawings, and to the characters of reference marked thereon, which form a part of this application.

This invention relates to improvements in wheels for general purposes, but is particularly designed for use in connection with self propelled tractors using any suitable power.

The object of the invention is to produce a wheel which will have a very effective traction effect against the ground irrespective of the character of the ground and particularly a wheel which will pull through plowed or other loosened earth without the chance of such earth impeding the progress of the wheel by piling or being pressed up in front of the same which gives to the wheel the effect of continually pulling up hill.

My improved wheel is provided with a traction means which causes it to grip firmly on slippery surfaces or on loosened earth surfaces; it is designed to continually pass the loose dirt, which is inclined to pile up in front of the wheel, through the body of the wheel, but still not in such a manner as to prevent the tractive operation of such wheel.

A further object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claims.

On the drawings similar characters of reference indicate corresponding parts in the several views.

Figure 1 is an end view of one of my improved wheels. Fig. 2 is a bottom view of the same. Fig. 3 is a sectional view of a cutter ring and supporting arms taken on a line X—X of Fig. 2.

Referring now more particularly to the characters of reference on the drawings, the

numeral 1 designates the hub of the wheel and the numeral 2 the spokes. In my improved wheel these spokes 2 are disposed on one side of the wheel and have outwardly projecting arms 3, each arm having a pair of spaced flanges 4. Secured to each set of said flanges 4 is an independent cutter ring or rim 5 consisting of a specially designed steel casting which comprises the said ring 5 which is beveled on its outer edge to form a cutter, there being a plurality of spaced projecting arms 5^a on each of the rings, said arms being disposed in equal spaced relation with respect to each other. These cutter rings or rims, as will therefore be noted, will also constitute the cutter supporting rim for the wheel leaving an intermediate clear space between said cutter rings, as seen clearly in Fig. 2. I then provide the tractive means of the wheel which consists principally of a plurality of cast steel angle grips or similar members 6 placed across the said rings 5 and secured to members 5^a. These members 6 may be disposed in a slightly inclined or in any other desired position and are of course spaced apart with relation to each other to form intermediate spaces cut between themselves and between the cutter rings 5. Thus as will be seen, there is a continuous clear space between the cutters 5 and the members 6 and while the projecting edges of the cast steel angle grip form a tractive surface for the wheel, still any loose dirt which would have a tendency to pile up in front of and impede the progress of a solid wheel would merely work and sift through the spaces between the members 5 and the members 6 in the forward part of the wheel and similarly would work or sift through the inside of the wheel to the ground again through the rear part of the wheel. This operation would also be materially aided by the cutter rings 5 which would cut through the dirt and not tend to impede its movement or cause it to clog thereagainst or between the members 6.

The large and effective tractive surface given by the projecting parts of the cast steel angle grips 6 will cause the same to grip against slideable surfaces such as wet ground or weedy ground and aid in the propelling of the tractor forward without loss of power. For traveling on roads or from one point to another when not under load, a smooth band may be bolted around these cast steel angle grips 6 and then such pro-

jections will not cut or injure the roads over which the tractor passes.

From the foregoing description it will be readily seen that I have produced such a device as substantially fulfills the objects of the invention as set forth herein.

While this specification sets forth in detail the present and preferred construction of the device, still in practice, such deviations 10 from such detail may be resorted to as do not form a departure from the spirit of the invention.

Having thus described my invention what I claim as new and useful and desire to 15 secure by Letters Patent is:

1. A device of the character described comprising a hub, spokes mounted on one end of said hub, projecting arms on the outer ends of said spokes, a plurality of 20 cutter rings secured to said arms in spaced relation and angle grips secured on said cutter rings in spaced relation, as described.

2. A device of the character described

comprising a hub and spokes, spaced cutter rings mounted on said spokes, each cutter 25 ring being provided with a plurality of projecting arms, said arms being disposed in spaced relation, and a plurality of gripping members mounted on said projecting arms, as described.

3. A device of the character described comprising the combination of a hub, spokes mounted on one end of said hub, a projecting arm on each spoke, a pair of spaced flanges on each arm, a cutter ring secured to 30 each of said flanges, said cutter rings being provided with a plurality of spaced arms, and gripping members secured to said spaced arms, as described.

In testimony whereof I affix my signature 40 in presence of two witnesses.

JOHN M. KROYER.
